By his Attorney,
Nelson W. Howard

UNITED STATES PATENT OFFICE

LOUIS GEORGE DINGELDEY, OF CLEVELAND, OHIO, ASSIGNOR TO UNITED SHOE MACHINERY CORPORATION, OF PATERSON, NEW JERSEY, A CORPORATION OF NEW JERSEY

WORK SUPPORT

Application filed July 10, 1929. Serial No. 377,159.

This invention relates to improvements in work supports and is illustrated herein as embodied in a fastening inserting machine of a type used in the manufacture and repairing of shoes.

In the repairing of shoes the thickness of the work piece into which fastenings are inserted varies over a wide range. The same machine is used, for example, both to attach soles to shoes by all-around stapling and to attach top lifts to heels of varying heights. It is, accordingly, desirable to provide a work support the height of which can be adjusted rapidly and with a minimum of labor. Since work supports used on metallic fastening inserting machines, particularly when the work is to be performed off the last as in the case of all-around stapling or nailing, are commonly provided with a clenching cavity the relation of which to the line of drive is critical, it is necessary so to construct the work support that heightwise adjustment thereof will not affect the position of the clenching cavity transversely of the line of drive. On the other hand, for example to facilitate the setting up of the machine, it is necessary to provide means by which the position of the clenching cavity can be adjusted transversely of the line of drive.

It is, accordingly, an object of the present invention to provide an improved work support adapted for use in fastening inserting machines of the type used in the manufacture and repairing of boots and shoes of such a character that its height can be more quickly and conveniently adjusted than is the case with the constructions of the prior art. It is a further object of the invention to provide an improved work support of such a nature that the work support can be adjusted heightwise without any possibility of disturbing the adjustment of its clenching surface transversely of the line of drive.

As illustrated herein, and in accordance with features of the invention, the work support comprises a horn vertically adjustable with respect to the horn post of the machine and provided with a ratchet engaged by a pawl also carried by the horn post, the construction being of such a nature that the

horn is held by the pawl and ratchet against movement away from its work supporting or clamping position (against downward movement, as illustrated) but can be freely moved by the operator toward its work clamping position when the machine is at rest. As illustrated, the pawl is provided with a tail or handle projecting outwardly so that it can be conveniently manipulated to release the support. This can be done by merely striking a light blow upon the tail of the pawl by downward movement of the hand of the operator. Such a construction permits the adjustment of the horn toward its work supporting position to be made conveniently while a work piece is on the horn, the position to which the horn is adjusted being determined by the thickness of the work piece. In doing this the operator grasps the horn of the work support and the work piece in one hand, holding them in their desired relation to each other and using his other hand to steady the work piece if necessary. As he lifts the horn to the desired position the ratchet clicks past the horn and holds the horn against downward movement.

In accordance with another feature of the invention, the illustrated machine is provided with improved means for making and maintaining the adjustment of the clenching surface of the horn transversely of the line of drive at all times, regardless of the heightwise adjustment of the work support. For this purpose a horn supporting or bracket member, which is secured to the horn post for rotation about the line of drive, is provided with an upstanding rod surrounded by a collar slidably mounted thereon and provided with a socket illustrated as an undercut bayonet slot receiving a ball formed on the end of an adjusting screw threaded through the horn and normally secured in position by a lock nut. The collar slides vertically on the rod as the horn is adjusted heightwise and thus prevents transverse movement of the horn relatively to the horn support and accordingly relatively to the line of drive.

With the above and other objects and features in view the invention will now be de-

scribed with reference to the accompanying drawings and pointed out in the claims.

In the drawings:

Fig. 1 is a side elevation of a staple inserting machine provided with a work support embodying the present invention;

Fig. 2 is a view on a larger scale of the work support and the fastening inserting instrumentalities of the machine, portions being shown in vertical section more clearly to disclose the construction;

Fig. 3 is a horizontal section on the line III—III of Fig. 2; and

Fig. 4 is a detail view on a larger scale than Figs. 2 and 3 of a portion of the means for maintaining the transverse adjustment of the clenching cavity relatively to the line of drive.

The work support of the present invention is illustrated herein as embodied in a fastening inserting machine having staple forming and inserting instrumentalities of the character disclosed in Letters Patent of the United States No. 1,016,930, granted February 13, 1912, on an application filed in the name of William H. Borden to which reference may be had for a fuller disclosure of such parts of the machine as it is unnecessary to describe and illustrate herein. In brief this machine comprises a column 10 carrying at its upper end a head 12 provided with wire feeding rolls 14 (Fig. 2) from which a wire 16 is fed to a pair of knives 18 which sever from it suitable lengths for the formation of staples. The staples are formed from the wire 16 by relative movement of an inside former 20 and outside formers 22, staples being driven through a nozzle 24 by a driver 26. The staple forming and inserting instrumentalities are operated from a main drive shaft 28 to which power is transmitted by clutch mechanism 30 from a belt pulley 32. The clutch mechanism 30 is controlled from a treadle 34 (Fig. 1) through a treadle rod 36, the arrangement being such that depression of the treadle 34 beyond a point determined by a lost motion connection 38 trips the clutch and causes the operation of the fastening inserting instrumentalities.

The machine is provided with a horn post 40 mounted for vertical sliding movement in a sleeve 42 carried by a bracket 44 secured to the column 10, the horn post 40 being raised through connections 46 by the earlier portion of the depression of the treadle 34 in a well-known manner so that the work piece in which a fastening is to be inserted (for example a shoe to which a sole or a half-sole is to be attached by all-around stapling or a shoe having a heel to which a top-lift is to be attached) is clamped under a relatively heavy spring pressure before the clutch is tripped.

Mounted at the top of the horn post 40 for rotary movement about the line of drive 65 is a bracket 50 provided with vertical ways

52 slidably receiving a downwardly extending stem 54 carried by a horn 56. The stem 54 of the horn 56 is provided with a ratchet 58 cooperating with a pawl 60 pivoted at 62 to the bracket 50 and yieldingly held in engagement with the ratchet 58 by a spring 64 so that the horn 56 can be moved upwardly while the machine is at rest without interference by the pawl 60 but is held against downward movement except when the pawl 60 is manually released. The pawl 60 is provided with a substantially horizontal tail or handle 66 projecting outwardly so that the pawl 60 can be released from the ratchet 58 by a light blow struck on the tail 66 by a downward movement of the hand of the operator.

The bracket 50 carries an upstanding rod 68 adjacent to the horn 56. Slidably mounted on the rod 68 is a collar 70. The collar 70 is provided with an undercut groove 72 in the form of a bayonet slot receiving a ball 74 formed on the end of a screw 76 threaded in a hole formed in the horn 56 and clamped in adjusted position by a lock nut 78. Thus it will be seen that transverse movement of the horn 56 relatively to the bracket 50 is prevented by engagement of the screw 76 with the collar 70 and heightwise movement of the horn is in no way interfered with. To prevent the escape of the collar 70 from the rod 68 by excessive upward movement of the horn 56 a collar 80 is secured to the upper end of the horn 56. When it is desired to adjust the position of the clenching cavity 82 carried at the end of the horn 58, either in setting up the machine or otherwise, it is only necessary to release the lock nut 78, turn the screw 76 to make the desired adjustment, and then tighten up the lock nut. In this way the desired critical adjustment of the clenching cavity 80 relatively to the line of drive can be easily made.

Assuming the work support to be in such a position that the horn 56 is too high to receive the work piece which is to be presented to the machine, the operator strikes the handle 66 of the pawl 60 thus releasing the pawl from the ratchet 58 so that the horn descends to its lowermost position. Then he places the work piece on the horn 58, holding the work piece between the end of the horn 58 and the nozzle 24 and at the same time grasping the portion of the horn 58 adjacent to the work piece with one hand so that he can move the horn and the work piece upwardly until the horn is spaced the desired distance below the nozzle of the machine. After the horn has been adjusted in this manner he depresses the treadle 34, first causing the work piece to be clamped between the horn 56 and the nozzle 24 and thereafter tripping the clutch thereby causing the insertion of a staple.

While the member 56 of the work support

of the illustrated machine is spoken of in this specification and the accompanying claims as a horn it should be understood that this is merely as a matter of convenience and is not intended as a limitation. Obviously the invention is not limited in its scope to a construction in which the work carrying member is of a curved formation of the general character herein disclosed and it is not intended that the claims shall be construed as limited to such a construction.

Having thus described my invention what I claim as new and desire to secure by Letters Patent of the United States is:

1. A fastening inserting machine having a work support comprising a horn, a support for the horn, means for moving the horn support to cause the horn to clamp a work piece against an abutment carried by the machine while a fastening is inserted therein, and adjustable connections between the horn support and the horn comprising a ratchet carried by the horn and a pawl carried by the horn support and engaging the ratchet, the construction being such that the horn is automatically held by the pawl and ratchet against movement relatively to the horn carrier away from its work supporting position but can be freely moved by the operator toward its work clamping position when the machine is at rest.

2. A fastening inserting machine having a work support comprising a horn, a support for the horn, means for raising the horn support to cause the horn to clamp a work piece against an abutment carried by the machine while a fastening is inserted therein, and adjustable connections between the horn support and the horn comprising a ratchet carried by the horn and a pawl carried by the horn support and engaging the ratchet, the construction being such that the horn is automatically held against downward movement relatively to the horn carrier but can be freely moved by the operator upwardly toward its work clamping position when the machine is at rest.

3. A fastening inserting machine having, in combination, fastening inserting instrumentalities, a work receiving abutment adjacent thereto, a work support comprising a horn post and a horn carried thereby, means for moving the horn post toward the fastening inserting instrumentalities thereby to clamp a work piece against the abutment, and adjustable connections between the horn post and the horn comprising a ratchet carried by the horn, a pawl carried by the horn post, a spring pressing the pawl into engagement with the ratchet to hold the horn against movement relatively to the horn post from its work clamping position but permitting the operator freely to move the horn relatively to the horn post toward its work clamping position when the machine is at rest, and

a handle on the pawl by which the pawl can be released from engagement with the ratchet when it is desired to adjust the horn away from its work clamping position.

4. A fastening inserting machine having a horn, a support for the horn, a treadle, connections from the treadle to the horn support for raising the horn support to cause the horn to clamp a work piece against an abutment carried by the machine while a fastening is inserted therein, and adjustable connections between the horn support and the horn comprising a ratchet secured to the horn and a pawl carried by the horn support and engaging the ratchet, the construction being such that the horn is automatically held by the pawl and ratchet against movement relatively to the horn carrier away from its work clamping position but can be freely moved by the operator toward its work clamping position when the machine is at rest.

5. A fastening inserting machine having, in combination, a horn, a support for the horn, means for raising the horn support to cause the horn to clamp a work piece against an abutment carried by the machine while a fastening is inserted, arranged to permit the work to be released from clamping pressure between the insertion of successive fastenings, and adjustable connections between the horn support and the horn comprising a ratchet carried by the horn, a pawl carried by the horn support, a spring pressing the pawl into engagement with the ratchet to hold the horn against downward movement relatively to the horn support but permitting the operator freely to move the horn upwardly toward its work clamping position when the machine is at rest, and a handle on the pawl by which the pawl can be released from engagement with the ratchet when it is desired to lower the horn.

6. A fastening inserting machine having a horn, a support for the horn relatively to which the horn is mounted for vertical and horizontal adjustment, a pair of interengaging stops carried by the horn and the horn support respectively, one of said stops being adjustable properly to position the horn transversely relatively to the fastening inserting instrumentalities of the machine, and a pawl and ratchet mechanism carried by the horn and the horn support constructed and arranged to secure the horn rigidly against movement relatively to the horn support away from the fastening inserting instrumentalities of the machine but to permit free adjusting movement of the horn by the operator toward the fastening inserting instrumentalities when the machine is at rest.

7. A fastening inserting machine having a horn, a support for the horn relatively to which the horn is mounted for vertical and horizontal adjustment, a pair of interengaging stops carried by the horn and the horn

support respectively, one of said stops being adjustable properly to position the horn transversely relatively to the fastening inserting instrumentalities of the machine, a pawl and ratchet mechanism carried by the horn and the horn support constructed and arranged to secure the horn rigidly against movement relatively to the horn support away from the fastening inserting instrumentalities of the machine but to permit free movement of the horn by the operator toward the fastening inserting instrumentalities when the machine is at rest and means for moving the horn and the horn support toward the fastening inserting instrumentalities of the machine when the machine is to be operated.

8. A machine having a work support comprising a horn constructed and arranged to clamp a work piece against an abutment carried by the machine, a rotary support for the horn, and adjustable connections between the horn support and the horn comprising a pawl and ratchet constructed and arranged so that the horn is automatically held against downward movement relatively to the rotary support from its work clamping position but can be freely moved by the operator upwardly toward its work clamping position while the machine is at rest, the pawl having a tail projecting approximately horizontally so that it can be readily struck by downward movement of the hand of the operator thereby releasing the pawl from the ratchet and permitting downward movement of the horn relatively to the horn carrier.

9. A machine having a work support comprising a vertically movable horn post, a horn carried by the horn post, a ratchet carried by the horn, a pawl carried by the horn post and engaging the ratchet thereby preventing downward movement of the horn relatively to the horn post, and a handle projecting from the pawl in position to be struck by downward movement of the hand of the operator thereby withdrawing the pawl from the ratchet and permitting downward movement of the horn relatively to the horn post.

10. In a fastening inserting machine, a work support for holding a work piece while fastenings are driven therein comprising a horn support, a horn carried by the horn support and provided with a clenching cavity, said horn being mounted for rotary adjustment about an axis out of alinement with the line of drive of the fastenings, and a screw connected both to the horn and to the horn support, movable with the horn parallel to the line of drive but normally secured against movement relatively to the horn, the connection of the screw to one of those members being adjustable transversely to the line of drive to adjust the position of the clenching cavity transversely of the line of drive.

11. A work support for a fastening insert-

ing machine comprising a horn post, a rotatable bracket carried at the upper end of the horn post, a horn carried by said bracket and mounted for vertical adjustment relatively thereto and for rotary adjustment about an axis out of alinement with the axis of rotation of the bracket, means for securing the horn to the bracket arranged to permit free adjusting movement of the horn relatively to the bracket toward the fastening inserting instrumentalities of the machine when the machine is at rest but to prevent movement of the horn in the opposite direction, and means for holding the horn against transverse movement relatively to the bracket comprising a screw adjustably carried by the horn and having upon its end a member located in a socket formed in a collar slidably mounted on an upstanding rod carried by the bracket.

12. In a fastening inserting machine, a work support for holding a work piece while fastenings are driven therein comprising a horn support, a horn carried by the horn support and mounted for rotary adjustment relatively to the horn support about an axis out of alinement with the line of drive of the fastenings, and interengaging members carried by the horn and the horn support respectively relatively adjustable to move the end of the horn and a clenching cavity formed therein transversely of the line of drive and comprising a screw adjustably carried by the horn and having on one end a ball located in a socket formed in a member carried by the horn support and freely movable with the horn parallel to the line of drive but secured against movement in any other direction.

13. A work support for a fastening inserting machine comprising a horn post, a rotatable bracket carried at the upper end of the horn post, a horn carried by said bracket and mounted for vertical adjustment relatively thereto and for rotary adjustment about an axis out of alinement with the axis of rotation of the bracket, means for securing the horn to the bracket arranged to permit free movement of the horn by the operator toward the fastening inserting instrumentalities of the machine when the machine is at rest but to prevent movement of the horn in the opposite direction, and means for holding the horn against transverse movement relatively to the bracket comprising a screw adjustably carried by the horn and having upon its end a ball located in an undercut bayonet slot formed in a collar slidably mounted on an upstanding rod carried by the bracket.

14. A fastening inserting machine having, in combination, fastening inserting instrumentalities and a work support constructed and arranged to present a work piece in fastening-receiving relation to said instrumentalities comprising two relatively adjustable parts connected by a screw threaded

into one of the parts and carrying upon its end a ball located in a socket formed in a member carried by the other part whereby the position of the two parts can be adjusted by rotation of the screw.

- 5 15. A fastening inserting machine having, in combination, fastening inserting instrumentalities and a work support constructed and arranged to present a work piece in
10 fastening-receiving relation to said instrumentalities comprising two relatively adjustable parts connected by a screw threaded into one of the parts and carrying upon its end a ball located in a socket formed in a member carried by the other part whereby the position of the two parts can be adjusted by rotation of the screw, and means for locking the screw against rotation.

16. A work support having two relatively
20 adjustable parts connected by a screw threaded into one of the parts and having on its end a ball located in an undercut slot formed in a collar slidably mounted on a rod carried by the other part whereby rotation of
25 the screw causes relative adjustment of the two parts.

17. A work support having two relatively adjustable parts connected by a screw threaded into one of the parts and having on its end
30 a ball located in an undercut bayonet slot formed in a collar slidably mounted on a rod carried by the other part whereby rotation of the screw causes relative adjustment of the two parts, and a nut on the screw for
35 locking the screw against rotation.

In testimony whereof I have signed my name to this specification.

LOUIS GEORGE DINGELDEY.
